UNITED STATES PATENT OFFICE.

WILFRED I. OHMER, OF DAYTON, OHIO, ASSIGNOR TO THE RECORDING AND COMPUTING MACHINES COMPANY, OF DAYTON, OHIO.

MACHINE FOR PRINTING CONDUCTORS' REPORTS OR THE LIKE.

SPECIFICATION forming part of Letters Patent No. 768,619, dated August 30, 1904.

Application filed April 8, 1903. Serial No. 151,595. (No model.)

To all whom it may concern:

Be it known that I, WILFRED I. OHMER, a citizen of the United States, residing at Dayton, in the county of Montgomery and State of Ohio, have invented certain new and useful Improvements in Machines for Printing Conductors' Reports or the Like, of which the following is a specification, reference being had therein to the accompanying drawings.

This invention relates to machines for printing conductors' reports and other documents, and has for its object to provide a machine whereby such reports or the like may be readily and rapidly produced in printed form, preferably in duplicate.

To this end the invention consists in certain novel features, which I will now proceed to describe and will then particularly point out in the claims.

In the accompanying drawings, Figure 1, is a side elevation of a machine embodying my invention in one form. Fig. 2 is a plan view of the same. Fig. 3 is a plan view with the upper part of the casing and the mechanism therein removed. Fig. 4 is a sectional view taken on the line xx of Fig. 5 and looking in the direction of the arrows. Fig. 5 is a sectional view taken on the line yy of Fig. 4 and looking in the direction of the arrows. Fig. 6 is a detail sectional view taken on the line zz of Fig. 5 and looking in the direction of the arrows. Fig. 7 is a detail view of a portion of the numbering mechanism. Fig. 8 is a plan section taken on the line ww of Fig. 7 and looking in the direction of the arrows. Fig. 9 is a detail perspective view of the conductor's key, and Fig. 10 is a view of an impression from the machine.

I will first describe the machine as organized for the purpose of printing duplicate conductors' reports to be used in connection with freight traffic, duplicate reports being produced by each operation of the machine, this form of the invention being the one chosen in the present instance for purposes of illustration and shown in the accompanying drawings. In the said drawings the machine is shown as housed in a casing made in two separable parts, the same comprising a lower portion 1, which

contains the feeding and impression and inking devices and their operating mechanisms, and an upper portion 2, which contains the printing-plate and the printing-wheels and their setting and resetting mechanisms. The upper portion has a flange 3 and shoulder 4, whereby it fits over and seats on the upper edge of the lower part, the latter having upwardly-extending lugs 5 near its rear end at each side, fitting within the upper part, and a curved flange 6, over which the cut-away end of the upper part fits, said lugs and flange guiding the part 2 when it is lifted at its forward end. Hooks 7, pivoted on each side of the part 1 near its front end, take over projections 8 on the part 2 to hold the parts together. On each side of the machine is located a guide-arm 9, the lower ends of which are secured to a shaft 10, mounted in the part 1 of the casing and having an arm 11, to which is connected one end of a spring 12, the other end of which is connected to the casing. The upper end of each arm 9 is provided with a slot 13, terminating in a notch or seat 14, and the upper part of the casing is provided with projections or screws 15, which travel in said slots. When the hooks 7 are freed and the front end of the part 2 of the casing is lifted, the spring 12 so acts upon the arms 9 as to cause the projections 15 to engage the notches 14 when the top has been raised to its limit and released or lowered a trifle, thus holding the top or cover of the casing in its raised position, from which it may, however, be readily released.

Mounted in the upper part of the casing is a printing-plate 16, having its impression-face directed downward and bearing printing characters, which will be best understood from an inspection of Fig. 10 and to which more specific reference will be hereinafter made. Through this plate are formed three slots or openings 17, extending transversely thereof at suitable intervals, and above each slot, extending longitudinally thereof, there is mounted in the part 2 a shaft 19. Each shaft has loosely mounted thereon a plurality of printing-wheels 20, having printing characters on their peripheries, which when in printing po-

sition are flush with the printing-surface of the printing-plate 16. Each printing-wheel has a pinion 21, with which it moves, and each pinion has meshing with it a gear-segment 22, said gear-segments being mounted side by side on a shaft 23, mounted in the upper part 2 of the casing. There are three of these shafts 23, one for each transverse row of printing-wheels and parallel with the shaft thereof. Each gear-segment has a handle or operating - lever 24, extending outward through a slot 25 in the top of the casing. Each printing-wheel has also a detent 26, pivoted on the shaft 23 and having a tooth 27 to engage the pinion 21 of said printing-wheel, said detent being acted on by a spring 28, abutting against a cross-bar 29 and an arm 30 of the detent 26. Each transverse row of printing-wheels is provided with a resetting mechanism by which all of the arms which have been moved from their normal or initial position may be simultaneously returned to said position. To this end each shaft 23 is provided externally of the casing with a crank or handle 31, by means of which it may be rocked, while internally of the casing said shaft is provided with arms 32, which carry a resetting-bar 33, which extends across the paths of all of the handles or levers 24. By turning the crank 31 the several levers 24 will be engaged by the bar 33 and the levers and printing-wheels will be reset to normal position. To avoid the necessity of overcoming the combined resistance of all of the detents of each row during this operation, I provide means for disengaging said detents during the resetting movement. To this end each shaft 23 is provided near each end with a cam 34, said cams forming in the present instance extensions of the arms 32 in a direction from the shaft 23 opposite to that of said arms. A rock-shaft 35 has arms 36, operated on by said cams 34 and preferably provided with antifriction-rollers 37 to engage said cams. Said shaft 35 has other arms 38, carrying a rod 39, extending across the machine adjacent to the arms 30 of the detents. A similar provision is made for each of the three sets of rows of printing-wheels. When one of the shafts 23 is operated to reset the parts, the cams 34 rock the shaft 35 and press the rod 39 against the arms 30, thus lifting and disengaging the detents, holding them disengaged until the resetting operation is completed.

The impression mechanism, located in the lower portion 1 of the casing, is actuated by a crank 40, secured on a shaft 41, which projects through the casing, at one side thereof, to receive the crank 40. The inner end of said shaft is provided with a bevel-gear 42, which meshes with a similar gear 43 on a vertical shaft 44, said gear 43 having a crank arm 45, to which is pivoted at 46 the forward end of a connecting rod or link 47, the rear end of which is pivotally connected at 48 to

the carriage 49. This carriage supports the impression and inking rollers and is composed of side pieces 50 and cross-bars 51. The side pieces 50 fit and slide in ways 52, which extend along the sides of the part 1 of the casing, said ways being vertically adjustable by means of screws 53 to bring the ways and carriage in proper relation to the printing-surface. The inking-roller (indicated at 54) is mounted in arms 55, hung on the front cross-bar 51, and has its under side inclosed in a housing 56, which also acts as a shield to prevent the paper from coming into contact with the inking-roller. A spring 57 in the form of a cross-bar having its ends mounted in the side pieces 50 and its central part connected at 58 to the central arm 55 serves to hold the inking-roller in contact with the printing-surface. The impression-roller (indicated at 59) is carried by arms 60, projecting from a sleeve 61, loosely mounted on the rear upper cross-bar 51, and the journals 62 of said impression-roller extend through slots 63 in the side plates 50 and into cam-grooves in the ways 52, which cam-grooves serve to hold the impression-roller in operative relation to the printing-surface during the forward motion of the carriage and in inoperative relation thereto during the return movement. To this end said cam-groove has an upper horizontal portion 64, a lower horizontal portion 65, and terminal inclines 66 and 67, uniting said upper and lower portions. In order to prevent the journals 62 from returning along the inclined portions 66 at the beginning of the forward motion of the carriage, one or each of the arms 60 is provided with a spring-pressed detent-pin 68, which engages a depression 69 in the adjacent side piece 51 and holds the roller up as its journals pass the upper ends of the inclined portions 66 of the cam-groove.

The printing is done upon a paper strip 70, drawn from a roll 71, mounted in a casing or holder 72, detachably connected to the front end of the casing by hooks 73. The strip is carried under the guard or housing 56 of the inking-roller and over the impression-roller, which latter presses it against the printing-surface during the forward motion of the carriage. The paper is stationary during this movement and is fed forward during the return movement of the carriage by means of feed-rollers 74 and 75, located near the rear end of the machine adjacent to a slot 76 in the casing, through which slot the paper issues. The upper feed-roller 74 is mounted in the lugs 5. The lower feed-roller 75 is preferably covered with rubber or the like and is mounted on a shaft 77, which is positively rotated at intervals to effect the feed. To this end the shaft 77 is provided with a gear 78, which meshes with a gear 79, mounted loosely on a stud-shaft 80. This shaft 80 carries a bevel-gear 81, having a ratchet 82

engaged by a spring-pawl 83 on the gear 79. The bevel-gear 81 meshes with a similar gear 84 on the rear end of a longitudinal shaft 85, provided with a spiral cam-groove 86, in which travels a projection 87 from the carriage 49. By this construction the feed-rollers are unaffected during the forward motion of the carriage, but are driven to feed the paper forward during the return motion thereof. The shaft 77 is projected through the casing and provided with a knurled head 88, by means of which the feed-rollers may be turned by hand when desired.

The machine shown is organized to print each report in duplicate, and for the purpose I provide a stop mechanism which will permit two successive operations of the printing mechanism and will then prevent its further operation, as well as an alarm or signal mechanism which will indicate the completion of the operations. For this purpose the shaft 41 is provided with a gear 89, which meshes with a gear 90 of double the number of teeth. The gear 90 is provided with a stop projection 91 and is mounted on a counter-shaft 92, extending across the casing and provided near its other end with an arm 93. A rock-shaft 94 is mounted in the casing parallel with the shaft 92, one end of said rock-shaft projecting beyond the casing to receive a knurled head 95, by means of which it may be operated. The shaft 94 has secured on it near one end within the casing a stop-arm 96, drawn into the path of the arm 93 by a spring 97, the motion of said stop-arm being limited by a pin 98, which travels in a slot 99 in said arm. At its other end the rock-shaft 94 is provided with a stop-arm 100, which is held by the spring 97 in the path of the stop projection 91 on the gear 90. Before starting to print it is necessary to rock the shaft 94 by means of the head 95, so as to permit the crank 40 to be started, and as soon as this is done the shaft 94 will be released, whereupon the stop-arms 96 and 100 will return to the position shown. The crank 40 may then be given two full turns, thus printing two complete duplicate reports, since the shaft 92 makes only one revolution for two of the shaft 41, but upon the completion of the two revolutions of shaft 41 the stop-arms 96 and 100 will be struck by the arm 93 and projection 91, respectively, and the machine will stop, requiring a positive release of the stop mechanism to permit it to be again operated.

The signal mechanism comprises a gear 101 of the same size as gear 90 and driven from the gear 89 by an idle pinion 102. The gear 101 carries an eccentric-pin 103, in the path of which lies a projecting arm 104, secured to a sliding bar 105, guided along the inner wall of the casing by screws 106, which travel in slots 107 in the bar. A spring 108 tends to move the bar against the action of the pin 103. The bar 105 carries a striker 109, in

the path of which is located a bell 110, so that as the second turn of the crank 40 approaches its close the pin 103, engaging the arm 104, pushes the bar to the left in Fig. 6 until at or just before the close of the turn of the crank 70 the pin clears the arm, whereupon the spring 108 will bring the bar 105 sharply back and cause the bell to sound and notify the operator of the completion of the cycle of operations. It will be noted that the arm 104 is 75 flattened or otherwise so shaped at its lower end as to prevent reverse travel of the pin 103, such flattening being shown at 111. This feature, in connection with the stop-motion already described, positively locks the machine 80 at the end of each cycle of operations.

It is sometimes desirable to provide for the consecutive numbering of the reports, both duplicates bearing the same number, and in that case I employ the mechanism shown in 85 Figs. 7 and 8, in which the bar 105 is provided with a pin 112, which projects through a slot 113 in the casing. A shaft 114, carrying number-printing wheels 115, is mounted in the wall of the casing, its outer projecting end 90 having an arm 116, slotted at 117, as shown in dotted lines in Fig. 7, to receive the pin 112. A hood or shield 118 incloses and protects said arm 116. The part of the shaft 114 within the casing carries the number-printing 95 wheels, which may be operated by any suitable operating mechanism—such, for instance, as that shown—to print consecutively a number one higher for each complete movement of the arm 116 and bar 105. The number-printing 100 wheels extend through a slot 119 in the printing-plate 16, so as to print upon the paper strip the desired number, which will be the same for two consecutive printings, since the wheels are only shifted after two revolutions of the 105 crank 40.

In order that each conductor may print his name upon his reports, I employ a conductor's key or type-bar 120 (shown in Fig. 9) and having thereon the necessary printing characters. This key may be inserted through a slot 120^a in the casing and fits face downward in a suitable seat in the printing-plate 16, so as to have its characters impressed on the paper strip.

Referring now again to the printing-plate 115 16, of which an impression is shown in Fig. 10, it will be observed that said plate contains thereon a suitable legend describing the nature of the report—as, for instance, the words "Conductor's report of freight trains"—and 120 as a subheading the name of the road—as, for instance, "Pennsylvania lines west of Pittsburgh." It also has the word "Conductor" adjacent to the seat for the conductor's key and the abbreviation "No." adjacent to the slot 125 or opening 119 for the consecutive-number-printing device. The remainder of the impression-face of the printing-plate is divided into three transverse rows or groups of spaces corresponding to the three shafts 19 and three 130

openings 17, through which the printing-wheels 20 extend. The first row of spaces receives the impression from the printing-wheels on the shaft nearest the rear end of the machine, 5 and these spaces have suitable headings on the printing-plate, all of which relate to the train. As shown, these relate to the section-number, the train-number, the engine initials, the engine-number, the kind of train, the point of 10 departure, indicated by the word "From," the destination, indicated by the word "To," the caboose-number, and the caboose-initials. An inspection of Fig. 2 will show that the top of the case has a corresponding series of scales 15 and the operating-levers are grouped together to correspond with the spaces and scales, each lever being provided with a pointer or index 121 to coöperate with the scale. Strips 122, carrying legends for each group corresponding 20 with the heading of the spaces on the printing-plate, serve to indicate the use of each group of levers. As an illustration, the first group contains a single lever operating a single printing-wheel having numerals to print the 25 section-number. The second group comprises three levers each operating a number-printing wheel to indicate the engine-number. The third group has a single operating-lever operating a printing-wheel having on its face the 30 initials of the various railway-lines. The next group of levers is three in number, each operating a number-printing wheel to print the number of the engine. The next group is a single lever operating a printing-wheel having 35 thereon abbreviations to indicate the kind of train. The next two groups of levers are five in number each, the first and last operating letter-printing wheels and the intermediate ones number-printing wheels, the stations 40 being indicated by letters and numbers combined. The next group is composed of five levers each operating a number-printing wheel to indicate the caboose-number. The last group contains a single lever operating a 45 printing-wheel like that of the third group to give the caboose-initials. Of course the number of levers and the character of the printing-wheels may be varied as occasion may require, as well as the number of groups of levers. 50 The central row of spaces on the printing-plate is devoted to the trip-record, and the spaces have headings to indicate the name of the initial stations, the month, the day of the month, and the time of starting, the name of 55 the terminal station, the month and day of the month of arrival, the time of arrival, the division, and the direction. The printing-wheels on the central shaft 19 are arranged in groups with suitable characters to enable 60 them to print the proper data in the spaces reserved therefor, and the operating-levers are similarly grouped and provided with corresponding scales and pointers and legends for each group. The row of spaces nearest 65 the front of the machine is reserved for the

particular car to which the report relates and has spaces thereon with suitable headings to indicate the kind of car, initials of tank and individual cars, the initials of line-cars, the initials of foreign cars, and the initials of cars 70 belonging to the particular system on which the report is made out. Of course only one of these last four spaces will be filled out. Then there are spaces for the car-number, the load-mark, the station where the car was taken, 75 and the station where the car was left. The printing-wheels and operating-levers of the shaft 19 nearest the front of the machine will be provided with corresponding characters, scales, and legends and will be grouped as required. 80

It will be noticed that the group of levers near the front of the machine includes those which require most frequent change, being changed for each car, while the other two 85 groups of levers when once set remain in the same position for all cars of the train.

In making up his report the conductor will move the several levers of each group to the proper position to print the necessary information, the position being indicated by the scales on the top of the casing. He also inserts his key, so as to print his name on the report. He then turns the crank 40 twice, thereby printing a duplicate report for the 95 particular car to which it refers, having thereon a consecutive number, which is the same on each of the two reports, and the two are fed together out of the machine, at the rear end thereof. They can be torn or cut off and 100 separated or not, as required. The levers of the series of groups nearest the front of the machine are then reset by means of the resetting mechanism and are then moved to indicate the necessary data as to the next car, whereupon 105 the locking mechanism is released by turning the head 95, and the printing operation is performed as before by turning the crank 40 twice. These operations are repeated until a 110 duplicate report has been printed for each 110 car of the train. When used on another train or trip, the levers of the central and rear groups must be reset and changed accordingly. It will be seen that the work can be 115 done with great rapidity and accuracy, that 120 reports can be duplicated to any extent with great facility, and that the reports are much more legible than written reports made under the circumstances usually prevailing. Consecutive numbering of the reports enables 125 them to be readily traced and is a safeguard against carelessness or errors.

While I have described the machine as a machine for printing conductors' reports, it is evident that by suitable changes in the 125 printing characters, &c., it may be used for printing other matter—such, for example, as tags for merchandise, indicating size, quality, origin, prices, colors, and other data. I therefore do not wish to be understood as limiting 130

myself to the precise details of construction hereinbefore described and shown in the accompanying drawings. For instance, by securing the operating-crank 40 to the shaft of 5 one of the large gears 90 or 101 only a single turn of the crank will be necessary to print the duplicate report. Again, the consecutive-number-printing mechanism may be operated directly from the impression-carriage 49, in 10 which case each car-report will bear a different number, or said mechanism may be temporarily thrown out of operation by moving the arm 116 out of the path of the pin 112, in 15 which case all of the reports printed while the mechanism is thus inoperative—as, for instance, all of the reports relating to a given train—will bear the same number.

In referring to the impression on the report of data relative to the train I include therein 20 data relative to the engine, which, as will be seen from the drawings and description, form a part of and are included in the train data.

Having thus fully described my invention, what I claim as new, and desire to secure by 25 Letters Patent, is—

1. A machine for printing conductors' reports, &c., comprising a printing-plate having printing characters thereon and openings therethrough, a plurality of parallel shafts, 30 one for each opening, each shaft having a row of independent printing-wheels thereon projecting through the opening into printing position, each printing-wheel being provided with a gear, and a corresponding plurality of 35 operating-levers for each row, each lever provided with a gear-segment meshing with a gear, whereby each printing-wheel may be independently set, the printing characters of each row of printing-wheels relating to the 40 same generic subject-matter, the printing-wheels and operating-levers of each row being divided into groups relating to the same specific subject-matter, a casing provided with corresponding rows of slots similarly divided 45 into groups, through which slots the operating-levers pass, said casing having indicating-headings for the rows and indicating-scales for the slots, in combination with feeding and impression mechanism for feeding a web to and 50 from, and impressing it against, the printing-surface formed by the plate and wheels, substantially as described.

2. A machine for printing conductors' reports, &c., comprising a printing-plate having printing characters thereon and openings therethrough, a plurality of shafts, one for 55 each opening, each shaft provided with a row of independent printing-wheels thereon projecting through the opening, each printing-wheel provided with a gear, a plurality of operating-levers for each row, each lever provided with a gear-segment meshing with a 60 gear, whereby each printing-wheel may be independently set, and resetting mechanism

whereby the levers and wheels of each row 65 may be simultaneously reset to their initial positions, in combination with feeding and impression mechanism whereby a web may be fed to and from, and impressed against, the printing-surface formed by the plate and 70 wheels, substantially as described.

3. A machine for printing conductors' reports, &c., comprising a printing-plate having printing characters thereon and openings therethrough, a plurality of shafts, one for 75 each opening, each shaft provided with a row of independent printing-wheels thereon projecting through the opening, each printing-wheel provided with a gear and a detent, a plurality of operating-levers for each row, 80 each lever having a gear-segment meshing with a gear, whereby each printing-wheel may be independently set, and resetting mechanism for simultaneously releasing the detents and returning the levers and wheels of each 85 row to their initial positions, in combination with feeding and impression mechanism whereby a web may be fed to and from, and impressed against, the printing-surface formed by the plate and wheels, substantially 90 as described.

4. A machine for printing conductors' reports, &c., comprising a separable two-part casing, spring-controlled arms pivoted to the lower member of the casing and having guide-slots with terminal seats, and projections on the upper member traveling in said slots and adapted to engage said seats, substantially as 95 described.

5. In a machine for printing conductors' reports, &c., a printing-plate having printing characters thereon, and openings therein, printing-wheels in said openings and means for setting the same, a seat in said plate, a removable type bar or key fitting in said seat 100 and carrying indicia identifying the operator, and feeding and impression mechanism for feeding a web to and from, and impressing it 105 against the printing-surface formed by the plate, wheels and bar or key, substantially as 110 described.

6. In a machine of the character described, the combination, with a printing-surface, and a reciprocating carriage having inking and impression devices and provided with a projection, of feed-rollers, a gear having a ratchet connection with one of said rollers, and a shaft having a gear meshing with the first-mentioned gear, said shaft being provided with a spiral groove to receive the projection of the 115 carriage, substantially as described.

In testimony whereof I affix my signature in presence of two witnesses.

WILFRED I. OHMER.
